US0D1075717S

(12) **United States Design Patent** (10) Patent No.: **US D1,075,717 S**
(45) Date of Patent: ** May 20, 2025

(54) **LOUDSPEAKER**

(71) Applicant: **Harman International Industries, Incorporated**, Northridge, CA (US)

(72) Inventors: **Soarivo Marina Andrianoely**, Shenzhen (CN); **Dario Distefano**, Shenzhen (CN); **Jiacheng Yu**, Shenzhen (CN)

(73) Assignee: **Harman International Industries, Incorporated**, Northridge, CA (US)

(**) Term: **15 Years**

(21) Appl. No.: **29/868,157**

(22) Filed: **Nov. 22, 2022**

(51) LOC (15) Cl. **14-01**

(52) U.S. Cl.

USPC **D14/215**

(58) **Field of Classification Search**

(57) **CLAIM**

The ornamental design for a loudspeaker, as shown and described.

DESCRIPTION

FIG. 1 is a top, front perspective view of a loudspeaker showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The broken lines in the figures illustrate portions of the loudspeaker that form no part of the claimed design.

1 Claim, 7 Drawing Sheets
